UNITED STATES PATENT OFFICE.

FRED T. MADSEN, OF MAYWOOD, ILLINOIS, ASSIGNOR, BY MESNE ASSIGNMENTS, TO
AUTOMATIC ELECTRIC INC., OF CHICAGO, ILLINOIS, A CORPORATION OF DELA-
WARE.

TELEPHONE SYSTEM.

Application filed March 28, 1924. Serial No. 702,506.

The present invention relates to telephone systems in general, but is concerned more particularly with telephone systems employing non-numerical primary and secondary 5 trunking systems.

The main object of the invention is the production of a new and improved non-numerical trunking system in which a plurality of backward hunting finder switches 10 and a plurality of forward hunting secondary switches linked together in pairs through an intermediate distributing frame, are provided.

Another object is the production of new 15 and improved circuit arrangements whereby a finder switch is prevented from starting in search of a calling line, and another finder switch is started instead, if all the outlets to first selectors associated with the 20 first mentioned finder are in use.

Still another object has to do with the provision of the necessary circuit arrangements whereby the finder allotter, common to a plurality of finders, contains all the necessary 25 starting and testing relays for the finders and for the associated secondary switches, only one connecting relay being provided for each finder and its associated secondary switch. As regards this feature, the present case may be considered an improvement on the co-pending application 30 of Stehlik, filed December 23, 1922, Serial No. 608,764.

The other objects have to do mainly with 35 the circuit details and are more or less incidental to those pointed out above, and, together with the foregoing, will be explained fully in the course of the description which is to follow.

Referring now to the drawings comprising a single sheet, the line of substation A terminates at the exchange in the banks of the finders, such as F, and also in the banks of the connector switches (not shown). The 45 secondary switch SS associated with the finder F through the jumpers on the intermediate distributing frame IDF, extends the calling line found by the finder F to a selector, such as S.

The subscribers' lines are divided into 50 groups, and there may be as many lines in a group as there are sets of contacts in the bank of the finder F, there being a sufficient number of finders provided for each group 55 of lines to handle the traffic from that group.

Also the first selectors, such as S, are divided into groups, and there may be as many selectors in one group as there are sets of contacts in the bank of the secondary switch SS. The number of groups of lines, 60 which is also the number of groups of finders, is of course determined by dividing the total number of lines by the number of lines in a group. The number of groups of first selectors is determined from a consideration of the total number of selectors which are required to handle the traffic carried by all the groups of finders, as given by the standard traffic curves. This figure, 65 that is, the figure denoting the total number of selectors, is divided by the number of selectors in a group and the result gives the number of groups required. The secondary switches paired with the finder switches are then assigned to the selector groups so that 70 there will be about the same number having access to the selectors in each group. Now in order that the entire system may be woven into one unitary network, the finders in the same group are, as far as possible, cross-connected on the intermediate distributing frame to secondary switches in different groups. For example, if there are six finders, such as F, in one group, each finder is 75 cross-connected with a secondary switch in a different group provided there are six secondary groups. However, if there are only three groups of secondary switches and six finders in one group, two finders are cross-connected with two secondary switches in 80 each of the three secondary groups. 85

From the above, it will be appreciated that the conductors associated with the finders may be permanently wired to the one side of the intermediate distributing frame 95 and that the conductors associated with the secondary switches may be permanently wired to the opposite side of the distributing frame, permitting jumpers to be run from the finder side to the secondary side 100 to cross-connect the finders and secondaries in any desired manner when the original installation is made, and also to permit the finders and secondaries to be readily regrouped at the distributing frame from time 105 to time as traffic conditions make it necessary or desirable.

The finder allotter FA contains the necessary start relays and testing relays for the 110 finder F and the secondary switch SS and

also allots a new finder for use when the previously allotted one connects with a calling line.

The busying relay 58 is energized by the chain of relays, of which relay 56 is one, when all the selectors, such as S, associated with the secondary switch SS become busy. Relay 58 renders all the finder switches which are connected to the secondary switches in that group non-selectable to the finder allotter FA, so that the finder allotter FA will allot finders connected with secondary switches in idle groups only.

The substation A is an automatic substation having the usual talking, signalling, and switch controlling devices.

The finder F is mechanically of the well known rotary type of switch whose wipers have no normal position and move in a forward direction only. The secondary switch SS is identical mechanically with the finder F. The finder allotter FA is also identical with the finder F, except that it has six wipers instead of three. Although it is not essential to the features of the invention, it is assumed that the selector S, whose circuits are only partially disclosed, is of the usual vertical and rotary type, having its bank contacts arranged in horizontal rows or levels.

The apparatus, having been described more or less in general, will now be described in connection with the detailed description of its operation. For this purpose it will be assumed that the subscriber at substation A desires to make a call, in which case he removes his receiver, closing a bridge across the line conductors 2 and 3. When this occurs, line relay 6 energizes through armatures 7 and 10 of cut-off relay 5 and places ground on start conductor 14 at armature 13. Line relay 6 also disconnects the private normal conductor 4 from cut-off relay 5 and connects it to ground at armature 11, thereby making the calling line busy immediately in the banks of the connector switches having access to it. Relay 6 also connects the test conductor 4', extending to the bank of the finder F, to cut off relay 5, thereby placing a battery potential upon the said test conductor 4' to enable the finder F to be stopped on the calling line.

Responsive to the ground potential being placed on start conductor 14, start relay 68 of the finder allotter FA energizes through the resting contact and armature 78 of relay 69; connects the lower winding of test relay 67 with test wiper 22 of the finder F at armature 75, through test wiper 84, the bank contact upon which it is standing, conductor 92, armature 39, and the resting contact and armature 27; and closes at armature 74 a circuit for stepping magnet 24 of the finder F, which includes armature 72 and its resting con-

tact, wiper 81, the bank contact upon which it is standing, conductor 87, the resting contact and armature 40, and the self-interrupting contacts of the stepping magnet 24. The further operation depends upon whether the wipers 21-23, inclusive, of the finder F are standing upon the bank contacts of the calling line or upon some other set. Assuming first that they are standing upon the bank contacts of the calling line, the lower winding of test relay 67, which, as above pointed out, is connected with the test wiper 22 of the finder F, is energized over conductor 4' and through cut-off relay 5 and opens the circuit of stepping magnet 24 of the finder F at armature 72 before the said stepping magnet 24 has had time to energize. The finder is thus prevented from rotating and the wipers remain in engagement with the contacts of the calling line. In the present case, however, it will be assumed that the wipers of the finder F are standing upon a set of contacts other than those of the calling line. In this case, no circuit is closed immediately over test wiper 22 for test relay 67 and the wipers 21-23, inclusive, of the finder F are advanced step by step in search of the calling line due to the buzzer-like action of stepping magnet 24 which interrupts its own circuit.

When the wipers 21-23, inclusive, of the finder F arrive upon the bank contacts in which the line of substation A terminates, test relay 67 is energized in series with cut-off relay 5 of the calling line over the above traced circuit. Cut-off relay 5, however, being marginally adjusted, does not energize at this time, owing to the fact that the resistance of the lower winding of relay 67 limits the current flow through the said cut-off relay 5. Relay 67, upon energizing, disconnects stepping magnet 24 and prepares a circuit for relay 25 of the finder F at armature 72, and at armature 73 closes a locking circuit for its upper winding through armature 60 and its working contact of start relay 68. The further operation depends upon whether or not the secondary switch SS has already found an idle trunk.

Returning now to the points at which start relay 68 first energized, this relay, in addition to closing the above pointed out circuits for controlling the finder F, starts the secondary switch SS as follows: At armature 76 relay 68 closes a circuit for test relay 66 and stepping magnet 35 of the secondary switch SS in series. This circuit includes wiper 86, the bank contact upon which it is standing, conductor 92, armature 39 and its resting contact, and the jumper 31. Coincident with the closure of the above circuit, test wiper 37 is connected to the above circuit at a point between test relay 66 and stepping magnet 35 at armature 125 130 135 140 145 150 155 160 ture 77, armature 77 being connected to relay 66 through armature 64 and its resting contact; and the working contact of armature 77 being connected to test wiper 37 through wiper 85, the bank contact upon which it is standing, conductor 91, and the jumper 32.

From this point the operation depends upon whether the trunk upon which the wipers of the secondary switch SS are standing is busy or idle. If it is idle, the connecting up of test wiper 37 does not have any particular utility at this time and test relay 66 energizes immediately in series with stepping magnet 35. Assuming the trunk to be busy, however, test relay 66 is short circuited by the ground potential encountered upon the grounded release trunk conductor of the busy trunk by test wiper 37 and does not energize, and stepping magnet 35 is energized through test wiper 37 and interrupts its own circuit, thereby advancing the wipers 36-38, inclusive, step by step in search of an idle trunk.

When an idle trunk is reached, which trunk it will be assumed is the one comprising conductors 53-55, inclusive, and extending to the selector S, there is no ground potential present on the test conductor of such trunk and stepping magnet 35 ceases to operate. Also test relay 66, being no longer short circuited, energizes in series with stepping magnet 35. Stepping magnet 35, however, does not energize in series with test relay 66, owing to the relatively high resistance of the latter. Upon energizing, test relay 66 closes a locking circuit for its upper winding at armature 62; disconnects stepping magnet 70 from the auxiliary test wiper 83 and shunts the interrupter contacts of stepping magnet 70 at armature 63; disconnects test wiper 37 of the secondary switch SS from the junction of its own winding and that of stepping magnet 35 and connects it to ground at armature 64, thereby making the seized trunk busy immediately; and at armature 71 prepares a circuit for connecting relay 25 of the finder F.

Responsive to the energization of relay 66 or to the energization of relay 67, whichever is completed last, the circuit of connecting relay 25 is completed and is as follows: from ground by way of the working contact and armature 74, armature 72 and its working contact, working contact and armature 71, wiper 82, the bank upon which it is standing, conductor 88, and connecting relay 25 to battery. Upon energizing, relay 25 locks itself to the release trunk conductor of the selector S, at armature 28, which is at this time grounded through wiper 85 of the finder allotter FA; disconnects cut-off relay 5 of the calling line from the lower winding of test relay 67 of the finder allotter FA at armature 27 and connects it to ground instead; and at armatures 26 and 29 extends the calling line through to the line relay 41 of the selector S. Responsive to the above mentioned operation of armature 27 of relay 25, the marginally adjusted cut-off relay 5 energizes and closes a locking circuit for itself at armature 8, and at armatures 7 and 10 disconnects line relay 6 and ground, respectively, from the conductors 2 and 3 of the calling line. Line relay 6 now deenergizes and removes ground from the start conductor 14 at armature 13; opens the initial circuit of cut-off relay 5 at armature 12, leaving cut-off relay 5 energized through its locking circuit which includes armature 8 and its working contact; and at armature 11 disconnects ground locally from the private normal conductor 4 and connects the said private normal conductor 4 to the cut-off relay 5, whereby the private normal conductor 4 is maintained grounded as long as ground is supplied to energize the cut-off relay 5.

In the selector S, line relay 41 energizes over the calling line, responsive to the attraction of armatures 26 and 29 of the connecting relay 25, and closes at armature 44 a circuit for release relay 42. Release relay 42 thereupon energizes and places ground upon the release trunk conductor 54 at armature 45 so as to maintain the connecting relay 25 energized after its initial circuit has been broken by the finder allotter FA.

In the finder allotter FA, as a further result of the application of the ground potential to wiper 82 to operate the connecting relay 25, as above pointed out, a circuit is closed for relay 69 which thereupon energizes; disconnects at another point the auxiliary test wiper 83 from stepping magnet 70 at armature 80; and at armature 79 connects the stepping magnet 70 in multiple with itself. Stepping magnet 70 thereupon energizes and moves the associated pawl (not shown) into engagement with the next notch in the wiper drying ratchet wheel but does not move the wipers 81-86, inclusive, the construction of the switch being such that the wipers are advanced upon the back stroke rather than upon the front stroke of the stepping magnet 70. Stepping magnet 70 also opens its local interrupter contacts but it does not interrupt its own circuit at this time, owing to the fact that the said interrupter contacts are bridged by armature 63 and its working contact of test relay 66.

As a further result of the energization of relay 69, it disconnects start relay 68 from the start conductor 14 at armature 78. Start relay 68, however, being slow acting, does not deenergize for the time being and holds its armature proper attracted long enough to permit the release relay 42 of the selector S to become energized and ground the release trunk conductor 54 as above pointed out.

During this interval, cut-off relay 5 energizes and line relay 6 deenergizes as hereinbefore pointed out, thereby removing ground from start conductor 14 at armature 13.

- 5 After the interval for which it is adjusted, the slow acting start relay 68 deenergizes and opens the initial circuit of relays 69 and 25 and of stepping magnet 70 at armature 74. This circuit, however, is now maintained closed by the connecting relay 25 of the finder F which is locked up through jumper 32 and wiper 37 to the grounded release trunk conductor 54 of the selector S. Relay 68 also opens the locking circuits of 10 test relays 66 and 67 at armature 78, whereupon these test relays deenergize. Test relay 66 removes the shunt from around the self-interrupting contacts of the stepping magnet 70 at armature 63, whereupon stepping magnet 70 deenergizes and advances the wipers 81-86, inclusive, into engagement with the next set of bank contacts. If the finder associated with the next set of contacts is 15 busy, test wiper 82 engages a grounded bank contact and relay 69 remains energized, extending the ground potential to stepping magnet 70, whereupon the said stepping magnet 70 continues to operate until an idle finder is reached, whereupon test wiper 82 20 engages an ungrounded bank contact and relay 69 deenergizes again connecting start relay 68 to the start conductor 14 to permit the pre-selected finder to be started as soon as start conductor 14 again becomes grounded upon the next call being made.

- When the calling subscriber manipulates his calling device in accordance with the first digit in the desired number, line relay 41 of the selector S responds and the selector 25 S raises its wipers 50-52, inclusive, in the usual manner opposite the desired level of bank contacts and then selects an idle trunk, whereupon switching relay 43 energizes; disconnects ground from armature 44 of the line relay 41 at armature 49; disconnects the test wiper 51 from the test circuit and connects it to the grounded release trunk conductor 54 at armature 47, thereby making the seized trunk busy immediately; and at armatures 46 and 48 disconnects the trunk conductors 53 and 55 from the windings of line relay 41 and extends them by way of wipers 50 and 52 to the line relay of the switch associated with the seized trunk. The line and release relays (not shown) of the seized trunk now energize and the latter places ground upon the associated release trunk conductor, extending ground through test wiper 51 and armature 47 and its working contact to the grounded release trunk conductor 54, before the slow acting release relay 42 has had time to deenergize. The remaining part of the connection is established in the usual and well known manner.

When the conversation is completed, ground is removed from test wiper 51 of the selector S in known manner upon the receiver being replaced at substation A, whereupon the finder F tests idle to the finder allotter FA, and relay 43 of the selector S and connecting relay 25 of the finder F deenergize. Relay 25 opens the circuit of cut-off relay 5, whereupon cut-off relay 5 deenergizes also.

The arrangement for causing idle finders to test busy to the finder allotter FA when the associated secondary switches have no idle outlets will now be explained. The group busying relay 58 has its circuit closed when all the chain relays, such as 56, are energized. Each of these relays is connected to the release trunk conductor of a selector switch in the same manner as relay 56. Accordingly, when all the selector switches accessible to the secondary switch SS are busy, all the relays, such as 56, are energized and the circuit of the group busying relay 58 is completed. Upon energizing, relay 58 grounds all the auxiliary test conductors, such as 59, in the associated group. Considering the test conductor 59, when this conductor is grounded, ground is extended through the intermediate distributing frame jumper 34 to the auxiliary test conductor 89 of the finder allotter FA and, assuming that the finder F is the one that is pre-selected when conductor 89 becomes grounded, a circuit is closed through the auxiliary test wiper 83, armature 80 and its resting contact, and the resting contact and armature 63 for the self-interrupting stepping magnet 70. Accordingly, stepping magnet 70 is advanced to the next set of contacts. If this next set of contacts tests busy to either of the test wipers 82 and 83, the wipers are advanced still further and they continue to be advanced until both wipers engage ungrounded contacts, it being understood, of course, that the various finders in the same group with F are cross-connected to different secondary groups, so that when all trunks in one secondary group are busy, others may be still available in other secondary groups.

It may happen that the auxiliary test conductor 89 becomes grounded while the finder F and the secondary switch SS are operating due to the fact that the start relay 68 is energized responsive to a call. In this case, the wipers 81-86, inclusive, are rotated and a new idle finder is allotted and, together with the associated secondary switch, is started in the usual manner. In the case now under discussion, the wipers of the allotter FA may pass over the contacts of busy finder switches and secondary switches with the circuits for the stepping magnets of such switches prepared at armatures 77 and 74. However, it is not possible to operate the

stepping magnets of a busy finder or a busy secondary switch, due to the fact that they are disconnected at such a time. For example, when connecting relay 25 of the finder F is operated, stepping magnet 24 is disconnected at armature 40, and stepping magnet 35 is disconnected at armature 39.

A further point that should be mentioned, perhaps, is that, although the finder allotter 10 FA can be stepped off a set of contacts while the finder F and the secondary switch SS are being operated, in case the secondary group becomes busy at such a time, the finder allotter cannot be stepped off a set of contacts 15 after the associated secondary switch has found an idle trunk because the auxiliary test wiper 83 is disconnected at armature 63 of test relay 66, which energizes when the secondary switch finds an idle trunk, as here- 20 before pointed out.

What is claimed is:

1. In a telephone system, lines, means including a plurality of backward hunting finder switches and a like number of forward hunting non-numerical switches for extending said lines when calling, said switches being connected together in pairs, each pair consisting of one backward hunting switch and one forward hunting switch, 25 each of said switches having a stepping magnet and an operating circuit therefor, an allotter, means responsive to a call on one of said lines for operating said allotter to directly close the circuit of the stepping magnet of an idle finder to start it hunting for the calling line and to directly close the circuit of the stepping magnet of the associated forward hunting switch to start said forward hunting switch also.

2. In a telephone system, two secondary switches having access, respectively, to two different groups of trunks, means for starting one of said switches in search of an idle trunk, and means responsive to a busy condition appearing on all trunks in the associated group before a trunk is found by the last named switch for stopping such switch and for starting the other switch.

3. In a telephone system, a group of lines, 50 a plurality of groups of trunks, a group of backward hunting switches for extending said lines, a plurality of groups of forward hunting switches, one group for each group of trunks and having access thereto, and circuit arrangements for connecting each of 55 said backward hunting switches with a forward hunting switch in a separate group.

4. In a telephone system, a plurality of lines, a plurality of trunks divided into 60 groups, a group of backward hunting switches having access to said lines, a plurality of groups of forward hunting switches, one group for each of said groups of trunks and having access thereto, circuit connections 65 between each of said backward hunting

switches and a forward hunting switch in a separate one of said groups, said circuit connections including an intermediate distributing frame interposed between said backward hunting switches and said forward 70 hunting switches to facilitate grouping and re-grouping.

5. In a telephone system, a plurality of lines and a plurality of trunks, a plurality of link circuits for connecting lines on which calls exist with idle trunks, each of said link circuits comprising a backward hunting finder switch for connecting with one of said lines and a forward hunting switch for selecting an idle trunk, a link allotter common to said links, two test relays in said allotter, means for energizing one of said test relays when the allotted backward hunting switch has completed its operation, means for energizing the other of said relays 85 when the allotted forward hunting switch has completed its operation, and means controlled by the said other testing relay for making the seized trunk busy regardless of whether the said backward hunting switch 90 has completed its operation or not.

6. In a telephone system, a plurality of lines and a plurality of trunks, a plurality of link circuits for connecting said lines with said trunks each of said link circuits comprising a backward hunting finder switch for connecting with one of said lines, a forward hunting switch for selecting an idle trunk, and a connecting relay for joining the two together, a link allotter common 95 to said links, two test relays in said allotter, means for energizing one of said test relays when the allotted backward hunting switch has completed its operation, means for energizing the other of said relays when the allotted forward hunting switch has completed 100 its operation, and means responsive to the completion of both energizations for energizing said connecting relay.

7. In a telephone system, a plurality of lines and a plurality of trunks, a plurality of link circuits for connecting said lines with said trunks, each of said link circuits comprising a backward hunting finder switch for connecting with one of said lines and a forward hunting switch for selecting an idle trunk, a link allotter common to said links, two test relays in said allotter, means for energizing one of said test relays when the allotted backward hunting switch has completed 110 its operation, means for energizing the other of said relays when the allotted forward hunting switch has completed its operation, and means responsive to the completion of both energizations for starting 120 said allotter in search of another idle link circuit.

8. In a telephone system, a plurality of lines and a plurality of trunks, a plurality of link circuits for connecting said lines 130

with said trunks, each of said link circuits comprising a backward hunting finder switch for connecting with one of said lines and a forward hunting switch for selecting an idle 5 trunk, each of said forward hunting switches having access to a separate group of trunks, testing means for advancing said allotter over busy link circuits, and auxiliary testing means for advancing said allotter over idle 10 link circuits in case the associated trunks are all busy.

9. In a telephone system, a plurality of lines and a plurality of trunks, a plurality of link circuits for connecting said lines with 15 said trunks, each of said link circuits comprising a backward hunting finder switch for connecting with one of said lines and a forward hunting switch for selecting an idle trunk, each of said forward hunting switches 20 having access to a separate group of trunks, testing means for advancing said allotter over busy link circuits, auxiliary testing means for advancing said allotter over idle 25 link circuits in case the associated trunks are all busy, and means responsive to the completion of the operation of the allotted forward hunting switch for rendering said auxiliary testing means ineffective.

10. A plurality of groups of lines, a plurality of groups of trunks, a group of finders assigned to each group of lines, a group of secondary switches having access to each group of trunks, a distributing frame, and jumpers on said frame connecting said finders and secondary switches together in pairs, said jumpers being so arranged that finders in each group are paired with secondary 35 switches in different groups.

11. In a telephone system, lines, means including a plurality of backward hunting finder switches and a like number of forward hunting non-numerical switches for extending said lines when calling, said switches being connected together in pairs, each pair 40 comprising one backward hunting switch and one forward hunting switch, each of said switches having a stepping magnet and an operating circuit therefor, an allotter, means responsive to a call on one of said lines for operating said allotter to directly close the circuit of the stepping magnet of an idle 45 finder to start it hunting for the calling line and to directly close the circuit of the stepping magnet of the associated forward hunting switch to start said forward hunting switch also, and means individual to each of 50 said pairs of switches for disconnecting the associated stepping magnets to prevent them from being operated by said allotter when 55 the switches are busy.

12. In a telephone system, two hunting switches, a plurality of lines terminating in bank contacts of one hunting switch, a plurality of trunks terminating in bank contacts of the second hunting switch, means 60

for connecting said first and second hunting switches as a unit, an allotter for preselecting an idle unit, means responsive to the initiation of a call for rendering said allotter effective to cause said unit to hunt for the 70 calling line and an idle trunk simultaneously and when both are found to connect the two.

13. In a telephone system, a calling line having a line relay and a cut-off relay, said line relay operative responsive to a call, a 75 line finder switch, having a connecting relay, and a trunk hunting switch connected together as a unit, an allotter switch for preselecting said unit and having a separate test relay for said finder and hunting switches, 80 means responsive to the operation of said line relay for rendering effective said allotter switch to cause said finder and hunting switches to find the calling line and an idle trunk, means responsive to the connection 85 with said line for operating said finder switch test relay in series with said cut-off relay, said cut-off relay remaining unoperated at this time, means responsive to the connection with said trunk for operating 90 said hunting switch test relay, means responsive to the operation of said test relays for operating said connecting relay, and means responsive to the operation of said connecting relay for operating said cut-off relay 95 to disconnect said line relay from the calling line.

14. In a telephone system, a group of lines, a group of double ended hunting switches each having access to all of the lines, a plurality of groups of trunks, each group of trunks being accessible to a different one of the switches, an allotter, means for operating the allotter responsive to the initiation of a call to cause a preselected switch to 100 hunt for the calling line and to hunt for an idle trunk in its associated group of trunks, means in the allotter operated when both the calling line and an idle trunk are found to disconnect the allotter from the switch and to select an idle switch for subsequent use, 110 and means in each switch effective when all the trunks accessible thereto are busy to cause the allotter to release the switch if it has been selected and to select a different 115 switch.

15. In a telephone system, a group of switches, a line accessible to all of said switches at one end thereof and different groups of trunks accessible to each of said switches in the other end thereof, an allotter associated with the line and with the group of switches, means in the allotter for preselecting an idle switch having access to an idle trunk, means responsive to the initiation of a call for operating the preselected switch to hunt for the calling line and to hunt for an idle trunk, means in the allotter for preselecting a different switch when the previously selected switch finds the calling 120 line.

- line and an idle trunk, and means for operating the allotter to select a different switch if before the previously selected switch finds a trunk all of the trunks accessible thereto become busy.
16. In a telephone system, a plurality of groups of trunks, a plurality of automatically operated switches each having access to a different one of said groups of trunks, a device for preselecting an idle one of said switches, means for operating said preselected switch to select an idle trunk, a relay in said device arranged to be operated when a trunk is selected, means in said device operated under predetermined conditions when said relay is operated, and operated if all trunks accessible to the switch become busy before the relay operates, said means being effective when operating and selecting a different switch.
17. In a telephone system, a plurality of groups of trunks, a plurality of automatically operated switches each having access to a group of trunks, a group of lines accessible to all of said switches, a device for preselecting an idle one of said switches, means operated responsive to the initiation of a call on any of said lines for operating said preselected switch to hunt for the calling line and for an idle trunk, a relay in said device operated when an idle trunk is found, means for operating said device to select a different switch if all of the trunks accessible to the preselected switch become busy before said relay operates, and means for operating said device to select a different switch when said relay operates and the calling line has been found.
18. In a telephone system, a plurality of lines, a plurality of groups of trunks, a switch associated with each group of trunks, means operated responsive to the initiation of a call to cause one of said switches to hunt for the line over which the call was initiated and simultaneously therewith to hunt for an idle trunk of said group of trunks, means associated with each group of trunks and operated when all of the trunks in the group are busy to stop the hunting movement of the switch associated with that group of trunks.
19. In a telephone system, a line, a plurality of groups of trunks, a plurality of switches having access to each group of trunks, all of said switches having access to the line, an allotter for preselecting an idle switch, means responsive to the initiation of a call over the line to cause the preselected switch to hunt for the line and simultaneously therewith to hunt for an idle trunk, and means in the allotter for starting another switch having access to a different group of trunks hunting if all of the trunks accessible to said first selected switch become busy before said first selected switch finds an idle trunk.
20. In combination with a line and a plurality of trunks of a plurality of switches each for establishing connections between said line and one of said trunks, an allotter for selecting a switch, means for operating said selected switch to hunt for an idle trunk and for the line, a relay in the allotter operated when an idle trunk is found, another relay in the allotter operated when both the line and a trunk are found, a motor magnet for operating the allotter, said motor magnet having contacts for interrupting its circuit, means comprising front contacts on said first relay for shunting said contacts, and means for establishing a stepping circuit for said magnet when all of the trunks accessible to the selected switch are busy, said means including back contacts on both of said relays.

In witness whereof, I hereunto subscribe my name this 24th day of March, A. D., 1924.

FRED T. MADSEN.
